CORSET

Webster Benjamin, Bristol, Conn.

Application March 2, 1931. Serial No. 519,607

1 Claim. (Cl. 2-39)

My invention relates to the class of garments that are employed for imparting shape to the body, and an object of my invention, among others, is the provision of a garment of this type having means for readily securing the meeting edges of the garment to give a continuously changing perpetual adjustment at every movement of the wearer.

One form of my improved corset in the making and use of which the objects herein set out, as well as others, may be attained, is illustrated in the accompanying drawing, in which—

Figure 1 is a view showing the garment in place ready for securing the meeting edges.

Figure 2 is a similar view showing the meeting edges of the garment secured and with the ends of the lacings secured.

Figure 3 is a detail view, scale enlarged, illustrating the manner of arranging the lacings.

Figure 4 is a detail view to the same scale illustrating the construction of one edge of the corset.

Figure 5 is a view in section on a plane denoted by the dotted lines 5-5 of Figure 4.

Figure 6 is a detail view illustrating a modified form of the hook.

Figure 7 is a detail view illustrating still another modified form.

In the accompanying drawing the numeral 5 denotes a corset that may be composed of any suitable material usually employed in garments of this type, and elastic fabric may be employed to such extent as may be desired. The garment may be shaped to fit such part of the person to which it is intended it shall be applied, my invention having to do particularly with the means for securing the meeting edges of the garment.

As shown and described herein this invention comprises eyes 7 and hooks 8 projecting from the opposite edges of the garment, and as shown particularly in Figure 4. These are arranged preferably with an eye 7 at the top and bottom of each edge of the garment, and preferably two hooks are employed at each edge of the garment, which hooks are substantially evenly spaced apart and between the eyes 7. The hooks particularly are rounded in cross section to provide for an easy slipping movement of the lacing around the hooks.

In the preferred form of construction the eyes and the hooks are secured in any suitable manner to steels 9, one of these steels being encased at each meeting edge of the garment and the eyes and hooks projecting through openings from each case in which the steel is located. The hooks

and eyes are preferably composed of metal and they are secured to the steels in any desired manner, as by rivets.

In the manufacture of corsets efforts are made to so construct the garment that its presence shall be obscured as much as possible, that is, to have the corset so smooth that its form will not be apparent through the light outer garments underneath which it is worn. To effect this purpose the eyes 7 and hooks 8 are made comparatively thin so that they will project to a minimum degree beyond the plane of the face of the fabric, and they are bent so that their ends will lie substantially with their planes in the same plane as the face of the fabric.

Lacings 10 are employed one for each edge of the garment, and each lacing is secured at its opposite ends to the eyes 7. When so secured the end portions of the lacings are each engaged with a hook on the opposite edge of the garment from which its end is secured, thereby creating loops 11 that come together between the hooks at the lengthwise center of each edge of the garment, and as shown in Figure 2. The loops may be tied at this point, if desired, but in the preferred form of construction I place hooks 12 at a distance from each meeting edge of the garment and preferably at a point opposite the interval between the two hooks, and as shown in Figure 1. These hooks are preferably secured to tabs 13 secured to the garment in any suitable manner, the hooks being secured to the ends of the tabs. When these hooks 12 are employed the lacings will be so secured to the eyes that the loops, when the lacings are engaged with the hooks and drawn taut to a required degree, will engage the hooks 12 and be thereby held from becoming loose.

In the preferred arrangement the hooks 8 on each edge of the garment may be placed to open both in one direction, either upwardly or downwardly, or in opposite directions, either upwardly or downwardly, but I prefer to arrange them as shown in the drawing in which they open in opposite directions toward that edge of the garment nearest which they are located. By providing only a few of the hooks, and by rounding them, the lacings are free to slide back and forth so that the corset may readily accommodate itself to movements of the body in various directions thereby maintaining a perfect adjustment upon the body.

Stocking supports 14 may be attached to the bottom edge of the corset in a manner common to garments of this type.

In that form of the device shown in Figures 6 and 7 the hooks are composed of wire twisted into spiral form, the lacing being engaged with a hook by placing said lacing across the spiral 5 in the groove near to the stem of the hook, as illustrated in dotted lines in Figures 6 and 7. By then moving the lacing along the twists of the spiral to the end thereof it will be extended through the hooks as shown in Figures 6 and 7.

10 In that form of the spiral hook shown in Figure 6 the stem 15 is secured to the corset steel as by a rivet passed through an eye in the stem of the hook, said hook 16 extending laterally of said stem. Two of the hooks are employed as in the 15 case of the garment hereinbefore described. Said hooks are placed opposite the edge of the steel so that the latter if extended widthwise would pass through the center of the spiral lengthwise thereof, the hooks therefore being located practically in line with the edge of the garment.

15 In that structure shown in Figure 7 the hook comprises a lop 17 that is secured to the steel as by means of rivets, the opposite ends of the 20 loop being extended as stems 18 and at the ends 25 of the stems the wire being twisted into spiral form to comprise the hooks 19 that extend in opposite directions and away from each other. The lacing is inserted by placing it crosswise in the 30 groove of the spiral next to one of the stems 18, the lacing being then passed around the groove of the spiral to the end thereof. The opposite end of the lacing is then in a similar manner en-

gaged with the other hook after which it will be seen that the lacing extends through both of the hooks as shown in Figure 7. It will be understood that the arrangement of these hooks will be the same as hereinbefore described that is with eyes at each end of each steel and with the hooks between the eyes.

20 In accordance with the provisions of the patent statutes I have described the principles of operation of my invention together with the device which I now consider to represent the best embodiment thereof; but I desire to have it understood that the device shown is only illustrative and that the invention may be carried out by 25 other means and applied to uses other than those above set out.

25 I claim:

30 A corset having a row of fastenings at each meeting edge, each of said rows comprising a pair of eyes at each end and a set of hooks intermediate of and appurtenant to each pair of eyes, lacings each secured at its opposite ends to said eyes on the same edge and arranged to interlace with the hooks to form a loop between the two sets of hooks at the center of the rows of fastenings, a tab secured at a distance from each meeting edge of the corset, and hooks secured to 35 said tabs and arranged to receive the loops of said lacings in taut condition forming a continuously changing perpetual adjustment at every 40 movement of the wearer.
